BATHING CAP

Winnie Carter, Wallington, England, assignor of
one-half to George Spencer Moulton & Com-
pany, Limited, London, England

Application July 19, 1934, Serial No. 735,952
In Great Britain September 25, 1933

2 Claims. (Cl. 2—68)

This invention relates to bathing caps with more especial reference to those made of india-rubber and provided with ear flaps or cavities.

Hitherto such caps have been subject to the disadvantage that when in use the water gains access under the rim of the cap, thereby wetting the hair of the wearer, and the present invention has for its main object to remove this disadvantage and provide a bathing cap which will be comfortable to wear, while preventing the access of water to the hair.

In accordance with the present invention there is associated or combined with the bathing cap an annular band of elastic waterproof material, preferably thin sheet india-rubber, having apertures for the wearer's ears, which encircles the head of the wearer during use and prevents the access of water to the hair.

Conveniently, the upper edge of the annular band is secured to the inner surface of the bathing cap by adhesive or in other appropriate manner, the lower edge being advantageously reinforced or rendered more durable, as for example by being of greater thickness, thereby also having a capability for a closer fit at the edge, and it will be appreciated that with such an annular band of thin sheet material having considerable elastic properties positioned at or near the lower marginal edge of the cap, the wearer's head may be gripped sufficiently closely to exclude water without discomfort, whereas this result could not be achieved with the thicker material of the bathing cap proper.

The apertures in the annular band for the passage of the wearer's ears preferably coincide with the cavities normally provided therefor in moulded india-rubber bathing caps, and such cavities will, with advantage, be open at their lower ends, e. g. adjacent the chin-strap so as to permit egress of any water which may have collected therein, the lower and preferably reinforced edge of the annular band in such case passing round the head under the ear apertures and retaining the hair out of contact with the water.

The invention will be further described with reference to the accompanying drawing which illustrates by way of example one embodiment thereof, and in which,—

Fig. 1 is a front elevation of the bathing cap equipped with the interior annular elastic band in accordance with the invention. Fig. 2 being a side elevation partly in section of the cap shown in Fig. 1.

The cap is a part-spherical form 1 of moulded india-rubber open at its lower end 2 for the insertion of the wearer's head and having ear

receiving cavities 3 which are connected by a chin-strap 4 retaining the cap on the wearer's head when worn, the ear cavities being so formed as to provide a duct 5 at their lower ends through which any water which may have collected in the cavities may escape.

Adjacent the mouth 2 of the cap and adapted to encircle the wearer's head is an annular band 6 of elastic material, preferably thin sheet india-rubber, the upper edge 7 whereof is united to the interior surface of the cap 1 by adhesive or in other appropriate manner, while the lower edge 8 is free of the cap and is reinforced by being of double thickness, it being appreciated that the band 6 is so positioned in the cap that its lower edge 8 encircles the wearer's head passing across the forehead under the ears and across the nape of the neck and being of elastic waterproof material effectively excludes water from access to the hair of the wearer.

The band is provided with small apertures 9 coinciding with the ear cavities 3 for the passage of the wearer's ears thereinto, such apertures being so dimensioned as closely to encircle the ears and thereby effectively exclude any water which may collect in the ear cavities 3 from passing through to the interior of the headband 6.

It will be understood that the apertures 9 will usually be provided when the annular band 6 according to the invention is associated with a cap having ear cavities such as 3 and may also be provided when the ear cavities are absent, since by such provision the band can closely encircle the head, although they need not necessarily be provided in these conditions.

It will also be understood that the invention is not limited in its application to the form of moulded bathing cap described which is only illustrated by way of example.

What I claim is:—

1. The combination with an india-rubber bathing cap having ear cavities, of an annular band of thin sheet india-rubber having apertures for the wearer's ears coincident with said ear cavities, the band being positioned in the bathing cap near the lower marginal edge thereof and having its upper edge secured to the interior surface of the cap while its lower edge is free to fit the head of the wearer during use, thereby preventing access of water to the hair.

2. In the bathing cap combination according to claim 1, the formation of the lower ends of the ear cavities as ducts permitting the outlet of any water which collects in said cavities.
